UNITED STATES PATENT OFFICE.

JOHN B. WILKINSON, OF ALLIANCE, OHIO.

ACCOUNTING SYSTEM.

Application filed November 3, 1924. Serial No. 747,415.

This invention relates to accounting systems and particularly to accounting systems capable of being used by professional men such as physicians, lawyers, etc.

5 The object of the invention, in general, is to provide a simple, rapid, visible, private, one-hand and one-writing system which will be of such flexibility that any number of accounts may be efficiently kept.

10 A particular object of the invention is to provide an improved mechanical contrivance for receiving the various account cards and readily exposing the desired portions thereof, for example, the portions containing the name and address of the patient, client, etc., and the balance due on account, to view, the contrivance being simple in construction, inexpensive to manufacture, easy to operate and adapted to be operated in a drawer opening, in the manner of a drawer in a suitable form of desk or other case.

15 Another object of the invention is to provide a visible card system for keeping accounts whereby the name of the patient or client, etc., and his address is written only once each year, the status of his account at all times being visible beside the name and address of the patient or client, etc., so that statements may be prepared rapidly 20 by merely scanning the visible portions of the card.

25 Another object of the invention is to provide on the cards, means whereby, not only the balance due is visible but the state of delinquency of the account and the number 30 of statements rendered are plainly visible.

35 The foregoing and other objects are obtained by the specific system described below and illustrated in the accompanying drawings but it is to be understood that the benefits to be derived from various features of the invention may be obtained in structures other than the specific ones shown. Accordingly the invention is not limited to the system shown and described.

45 Of the accompanying drawings:

50 Figure 1 is a perspective view of a portion of a desk, illustrating the manner in which the system of the invention may be mounted and used therein;

55 Figure 2 is a plan view of a portion of the system when not in use;

Figure 3 is a front elevation thereof;
Figure 4 is a side elevation thereof;
Figure 5 is a front elevation of the system when in use;

60 Figure 6 is a side elevation of a portion thereof;

Figure 7 illustrates the first card prepared when the account is started or the initial card of the year, if the account runs over from the preceding year;

65 Figure 8 illustrates the cards subsequently employed for the entry of various items such as the subsequent calls of a physician;

Figure 9 is a rear elevation of one of the card-containing sections;

Figure 10 is a side elevation thereof;

Figure 11 is a section on line 11—11 of Figure 12;

70 Figure 11^a is a detail section illustrating the manner in which the card-containing sections cooperate.

Figure 12 is a front elevation thereof; and

75 Figure 13 is a perspective view of an auxiliary container employed with the sections shown in Figures 9 to 12, inclusive.

80 Referring to the drawings, 20, 20 are sections for containing the account cards. These sections are preferably formed of metal and are arranged to be slid relatively to each other, in the manner illustrated in Figures 1, 5 and 6, by being provided on their backs with metallic straps 21, 21 (Figures 9 to 12) and on their faces with vertical flanges 22, 22, the flanges 22 on one section being adapted to engage under straps 21 of the preceding section (Figure 11^a).

85 As is clearly apparent in Figure 12, the flanges 22 extend to a distance equal to the width of the sheet metal from which the sections are formed from the bottom of the section, so that the lower edges 23, 23, when engaged with straps 21 at 24 (Figure 10), will hold the sections in alignment as shown 90 in Figure 5. The flanges 22 are cut away downwardly from the tops of the sections a distance equal to the depth of the visible portions of the cards to be used therein so that the upper edges 25, 25 of the flanges 100 will engage the portions 26 (Figure 10) of straps 21 to hold the sections in stepped relation in the manner shown in Figures 1, 5 and 6.

It will be apparent from the foregoing that the back of each section forms the front of the section immediately behind the same. The front for the first section is, however, 5 formed of a plain plate 27 either of metal or of the material of the desk, formed preferably in a manner similar to the fronts of the drawers in the desk. The plate 27 is provided with straps 21 for sliding on the 10 flanges 22 of the first section and with a knob 28 and with a suitable form of lock indicated at 29.

In order to economize on the use of metal, the bottoms of the sections are formed of 15 bent over flanges 30 which need not extend over the entire bottom since auxiliary containers 31, 31 (Figure 13) of suitable material such as card board are preferably provided for mounting in sections 20. The containers 31 comprising box-like structures each formed with a front wall 32, provided with a tab 33 on its upper end, side walls 34 and 35 and a bottom 36. The containers 31 are preferably so formed that two or more 25 may be placed in each section 20 to divide it into a number of removable compartments as indicated in Figures 1, 2, and 5, the container 31 being easily removable by engagement of tabs 33 with the fingers.

30 In Figures 7 and 8, the preferred forms of cards for use in the system are shown. These comprise the initial cards 37 and the subsequent cards. Written across the tops of these cards are the abbreviated names of 35 the months whereby a record of the statements rendered is kept. Immediately beneath the names of the months on the left of the cards is a space indicated at 38 for the name and address of the patient or client, etc. On the right of space 38 are two spaces 40 39 and 40, the upper one 39 being for the balance and the lower one 40 for the amount forwarded from a preceding card, for example, the card of the preceding year when 45 the account runs from one year to another. The spaces 38, 39 and 40 constitute the visible portion of card 37 when sections 20 are in the position shown in Figures 1, 5 and 6.

Beneath the space 38 is a space 41 for the 50 date services were rendered, a second space 42 below space 41, designating to or for whom the services were rendered, and a third space 43 below space 42 for the age and occupation of the patient, client, etc. 55 Beneath space 40 and to the right of space 41 is a space 44 for the amount charged when the account was instituted, a space 45 below space 44 for the total of the amounts forwarded and charged and a space 46, below 60 space 45 for the amount paid on account. Below spaces 45 and 46 the lower portion 47 of the card is blank for the insertion of remarks, the health record of a patient, etc. Card 48 is in every way similar to card 37 with the exception that the

card is cut away at the top so that the names of the months and the name and address of the patient or client, etc., of card 37 may be used throughout the year. As many of cards 48 are employed with the initial card 37 as 70 are necessary to cover the items entered in the account and the status thereof, the spaces 39 and 40 of card 48 being on a tab adapted to appear at the right of the space 38 on card 37 when cards 48 are placed in front 75 of card 37.

In the use of the system, which will here be explained in connection with a physician's account, when a first call is made, the card is filled out in the manner shown in 80 Figure 7. If the wife of Mr. James L. Smith, for example, has called the doctor, after the visit he enters the name of James L. Smith and his address in space 38. In space 41 he enters the date of the call, October 31, 1924; in space 42 he places the patient's name, Mrs. J. L. Smith and in space 43, her age, 35, and her occupation, housewife. In space 47 the condition of Mrs. Smith may be entered. In space 44 he 85 enters the charge (\$25.00) for the call and since this is a new account he enters the same amount (\$25.00) in space 45. If Mr. Smith pays him \$15.00 prior to the first of the month or whenever statements are 90 mailed, this is entered in space 46. The amount paid is then subtracted from the total in space 45 and the balance carried up to space 39 where it is plainly visible.

When a second call is made, a card 48 is 100 used. Assuming that the daughter, Margaret, of Mr. and Mrs. Smith was ill on December 21, 1924, the date of the call, December 21, 1924 is entered in space 41, the name Margaret Smith in space 42, the age, 105 5, of Margaret Smith and her occupation, none, in space 43. The condition of Margaret Smith may be entered in space 47. The amount, \$10.00, forwarded from the first card is placed in space 40, the charge 110 \$25.00 for the second call is placed in space 44, the total of the above amounts, \$35.00, is placed in space 45, and if Mr. Smith pays \$15.00 on account before January 1, 1925, this is placed in space 46 and subtracted 115 from the amount \$35.00, in space 45, the balance \$20.00 being carried up to space 39.

Since cards 48 are placed in succession in front of card 37, all the cards being placed in containers 31 in sections 20, the system 120 always shows the status of the account of each party at a glance, the name of the patient and his address being written only once a year.

When the statements are prepared the sections 20 are slid outwardly from the drawer opening, and are caused to assume the positions as shown in Figure 1, as will be understood. The names and addresses and balances due are then copied onto the memo- 125 130

random statements to be mailed the patients. The month for which the statements are mailed is checked on the name of the month appearing at the tops of card 37. Accordingly when an account becomes delinquent it appears on the visible portion of the cards that a statement has been mailed for several months with no response. Vari-colored cards similar to cards 37 and 48 may then be substituted to more contrastingly call attention to the delinquency of the account.

It is to be noted that in practice what little mechanical operation the system may require may be accomplished by the use of the left hand only, the right hand being free to write in entries or to fill in memorandum statement blanks. Any suitable form of stop may be employed on the last section to prevent entirely removing the sections from the drawer opening by accident.

Modifications of the invention may be resorted to without departing from the spirit thereof or the scope of the appended claims.

What is claimed is:

1. An account system comprising a plurality of sections for receiving account cards, and means for connecting said sections for limited, relative, sliding movement, said means comprising straps on the backs of said sections and flanges on the fronts of said sections, the flanges of one section being slidably embraced by the straps of the preceding section.

2. An account system comprising a plurality of sections for receiving account cards, and means for connecting said sections for limited, vertical sliding movement relative to each other, said means comprising straps on the backs of the sections and flanges on the fronts of the sections, the straps on one section slidably embracing the flanges on a succeeding section.

3. An account system comprising a plurality of sections for receiving account cards and adapted to be moved inwardly and outwardly of a drawer opening, means for connecting said sections for limited, vertical sliding movement relative to each other, said means comprising straps on the backs of the sections and flanges on the fronts of the sections, the straps on one section being adapted to slidably embrace the flanges on a succeeding section, and a front plate having straps on its rear face adapted to slidably embrace the flanges on the foremost section so as to be capable of limited, vertical movement relative to said foremost section.

4. In an account system, a plurality of sections slidable on each other, and means for slidably connecting the sections together so that they will assume a stepped formation, said means comprising a strap on one section and a flange on another section, the flange being embraced by said strap and being of a length less than that of the strap

by a distance equal to the desired amount of displacement between the sections when in stepped formation.

5. In an account system, a plurality of relatively slidable sections for holding account cards each section comprising an open frame, and an auxiliary container seated in each section.

6. In an account system, a plurality of relatively slidable sections for holding account cards each section comprising an open frame, and an auxiliary container removably seated in each section.

7. In an account system, a plurality of relatively slidable sections for holding account cards each section comprising an open frame, and a plurality of auxiliary containers seated in each section.

8. An account system comprising, in combination, a plurality of sections connected together but movable into stepped relationship, sets of cards adapted to be received in said sections so that portions thereof are visible, each of said sets comprising an initial card having a space for the name of the debtor and a space for the balance due on the visible portion thereof and a subsequent card adapted to be placed in front of the initial card, the subsequent card being cut away at the portion corresponding to the name space on the initial card but having a visible portion provided with a space for the balance due.

9. A card system for keeping accounts comprising a set of cards including an initial card and one or more subsequent cards, said initial card having a space adjacent its upper edge for a name, and a space, also adjacent the upper edge, for a balance, said subsequent cards being adapted to be placed in front of the initial cards and being so formed that the name space on the initial card will be visible, the subsequent cards each having a tab overlying the balance space on the initial card and providing a space on the tab for a subsequent balance.

10. A set of cards for use in an account system comprising an initial card having a space adjacent its upper edge for a name, a space also adjacent its upper edge for a balance due, and means extending across the initial card, also adjacent its upper edge for indicating statements rendered, and a subsequent card having the portion corresponding to the name space of the initial card and that portion on which the months of the year are indicated cut away, thus providing a tab containing a space for a balance due, the tab being adapted to overlie the corresponding portion of the initial card.

11. An account system comprising an initial card and subsequent cards each having portions adapted to be rendered visible and other portions normally invisible, said initial card having a space for a balance due

on its visible portion, said subsequent cards having the portion corresponding to the first space cut away but being otherwise similar to the initial cards, whereby the name and address need be written only once each year.

12. A set of cards for use in an account system comprising one card having an upper marginal part of which contains means for

indicating statements rendered, and one or more other cards formed with tabs adapted to overlie part of the said marginal portion, said cards as a set being so constructed that means indicating statements rendered will be visible at all times.

JOHN B. WILKINSON.
